Inventor
Louis A. Birch
By his Attorney
Morelant and Kilson

UNITED STATES PATENT OFFICE.

LOUIS ARTHUR BIRCH, OF MINNEAPOLIS, MINNESOTA.

VENTILATED CLOSET BOWL.

Application filed August 20, 1924. Serial No. 733,097.

To all whom it may concern:

Be it known that I, LOUIS ARTHUR BIRCH, a citizen of the United States, residing at Minneapolis, in the county of Hennepin and 5 State of Minnesota, have invented certain new and useful Improvements in Ventilated Closet Bowls; and I do hereby declare the following to be a full, clear, and exact description of the invention, such as will enable others skilled in the art to which it 10 pertains to make and use the same.

My invention provides a simple and highly efficient ventilated closet bowl and, generally stated, consists of the novel construction, arrangement and combinations of 15 devices hereinafter described and defined in the claim.

In the accompanying drawings, which illustrate my invention, like characters indicate 20 like parts throughout the several views.

Referring to the drawings:

Fig. 1 is a front elevation showing the improved bowl, some parts being in vertical section on the line 1—1 of Fig. 2;

Fig. 2 is a side elevation of the bowl, some parts being in vertical section on the line 2—2 of Fig. 1;

Fig. 3 is a horizontal section taken on the irregular line 3—3 of Fig. 1; and

Fig. 4 is a fragmentary vertical section on the line 4—4 of Fig. 3.

The bowl is indicated as an entirety by the numeral 5, and hinged thereto is the customary seat 6 and cover 7. Secured on 35 top of the bowl and acting as stops for the seat 6 are segmental stop strips 8 and 9 that are spaced to form air passages at 10 that are extended forward of the rear half of the bowl. These stop strips are preferably 40 of some slightly pliable material, such as wood fibre, cork, or leather. The bowl is provided with the customary perforated water-flushing passage 11 that is connected to a water intake port 12 formed in the rear 45 extension of the bowl. This port 12, at the inner surface of the bowl, has a depending discharge nozzle 13 that is slightly oblique, as best shown in Fig. 1, so that it will deliver water across the rear portion of the

interior of the bowl. The numeral 14 indicates a short pipe sleeve cast into the port 12 to which the water supply pipe may be connected. At one side of the water intake port 12, the rear extension of the bowl is formed with an air outlet port or passage 15 that flares inwardly to the interior of the bowl and extends under the flushing passage 11. The numeral 16 indicates a pipe sleeve cast into the outer extremity of the port 15, in which will be connected a vent pipe that will be extended to a flue or chimney or other sort of draft which will produce a constant flow of air from the bowl and thereby produce the required ventilation. It is also important to note that, when the seat and cover 65 are lowered, or when the draft through the seat is closed, air will be drawn in only through the ports 10 and from thence immediately below the seat into the air outlet port 15. This, as is obvious, will produce 70 the best kind of ventilation.

It will be noted that the air outlet port 15 opens into the rear portion of the bowl immediately under the flushing passage 11 and at one side of the longitudinal axis of the 75 bowl, and that the discharge passage of the nozzle 13 terminates approximately at the longitudinal axis of the bowl and is obliquely arranged so as to direct a flushing stream immediately under the air outlet 80 port.

What I claim is:

A closet bowl having a perforated water-flushing passage extended in and around its rim portion and provided with an air outlet 85 port opening into the rear portion of the bowl immediately below said flushing passage and at one side of the longitudinal axis of the bowl, said bowl further having a water-flushing nozzle with a discharge passage, 90 the delivery portion of which is located lower down than said air outlet port approximately on the longitudinal axis of the bowl and is obliquely extended so as to direct a flushing stream under the said air 95 outlet port.

In testimony whereof I affix my signature.

LOUIS ARTHUR BIRCH.
